UNITED STATES PATENT OFFICE.

JOSEPH J. STOCKDON, OF SOMERVILLE, MASSACHUSETTS.

ELEBOW CONNECTION FOR RADIATORS.

No. 902,696.

Specification of Letters Patent

Patented Nov. 3, 1903.

Application filed July 26, 1905. Serial No. 271,378.

To all whom it may concern:

Be it known that I, JOSEPH J. STOCKDON, a citizen of the United States, residing at Somerville, in the county of Middlesex and State of Massachusetts, have invented certain new and useful Improvements in Elbow Connections for Radiators, of which the following is a specification.

This invention relates to elbow connections in the return-pipes from radiators heated by either the vapor or the steam system, and has for its object the provision of an improvement in the elbow, whereby it may be connected with a radiator heated by either of the systems described, and will serve to conduct the exhaust from the radiator to a pipe leading to another part of the system.

A further object of the invention is the provision in an elbow provided with a trap and a diaphragm above said trap, of a device for closing a port in the diaphragm when the steam system is employed, and for opening said port when the steam connection is omitted and the vapor-system is in use.

5 In the accompanying drawings, Figure 1 is a side view partially in longitudinal, vertical section of one form of the invention, showing the detachable steam-connection, the vent in the diaphragm and the screw being enlarged. Fig. 2 is a longitudinal, vertical section illustrating the invention as it appears when the steam-connection is omitted the vent in the diaphragm also being enlarged; and Fig. 3 is a view similar to Fig. 1, showing 35 a modified form of elbow.

Like numerals designate similar parts throughout the several views.

Referring to the drawings, the numeral 1 designates a radiator of any desired kind, and 40 2 an elbow showing my improvement applied thereto, said elbow being threaded into the radiator, as at 3, and containing a trap or pocket 4, above which, in the construction illustrated in Figs. 1 and 2, is disposed a diaphragm or partition 5. In this diaphragm is 45 formed a port 6 shown enlarged, which is left open as illustrated in Fig. 2, when what is known as the "vapor-system" is employed for heating the radiators, and is closed by a screw or other device 7, when steam at higher 50 than atmospheric pressure is employed as the heating-agent. To the elbow is attached, by an ordinary coupling 8, a conduit 9 leading to any desired point, for instance, the return- 55 pipe of the system.

When used with the steam-system a de-

tachable connection 10 is employed, said connection being applied at one end to the radiator, and communicating with a small port or vent 11 thereof, as illustrated in Fig. 1, 60 and the port 6 in the diaphragm 5 is closed by the screw or other device 7.

When vapor is employed as the heating agent, the port 6 is left open, the steam-connection 10 is removed, and the opening 65 through which said connection was attached to the elbow is closed by a screw-plug 12, as illustrated in Fig. 2.

In the vapor or low-pressure system, as in the steam-heating system, the exhaust from 70 the radiators occurs through the elbow 2, and in the steam-heating system it is important to permit air contained in the radiators to be driven off through the vent 11, pipe 10 and 75 the elbow described.

Steam as it leaves the radiators is condensed, and the water of condensation enters the trap 4, and seals the elbow. It is important in either system to provide a large 80 conduit in the elbow for the reception of the water of condensation, and also for air displaced from the radiator by the entrance of the heating agent therein.

When the low pressure or "vapor" system is employed the conduit 10 is removed from 85 the part of the radiator containing the vent 11, the hole in the elbow is closed by the plug 12, and the port in diaphragm 5 is opened by withdrawing the screw or other device 7, 90 the result being that water of condensation from the radiators will pass through said elbow, fill and seal the trap 4, and be conveyed to the return pipe, the air driven off by the vapor escaping over the trap through 95 the opening 6, and the pressure being below that of the atmosphere but a small amount of vapor will follow the air through the small vent 6.

In order to provide as large a space as possible for the water of condensation and for 100 the air and steam discharged through the small port 11, I have illustrated in Fig. 3, a modification of the elbow in which a circular chamber 13 is formed therein. In this modification the return-pipe from the radiators 105 is designated by 14, and is shown provided with a circular boss or enlargement 15, externally threaded to receive an internal thread 16 on a reduced end 13' of the elbow adjacent to said chamber. This enlargement 110 provides free space for the discharge of water of condensation, and the air or small

amount of steam passing through the vent 11. In the modification the return-pipe 14 may be of any desired capacity, and is curved downward at 14' to discharge the 5 water of condensation from the radiators into the trap 17, and the screw 7 is inserted into a port 6 on a line parallel to the inner wall 18 of the discharge end of the elbow, as 10 illustrated in Fig. 3,—said screw being located above the water-line of the trap. By forming the chamber 13 in the elbow as illustrated in said Fig. 3, space is also afforded for the reception of the return-pipe 14, and for enabling the elbow to be readily placed 15 in position upon said pipe.

When it is desired to detach the screw 7, this can readily be effected by removing the coupling 8, and inserting a screw-driver through the bore of the elbow, to engage the 20 head of said screw.

Any form of closure may be employed as a means for opening or closing the port 6 in either the diaphragm 5, or the return-connection 14, without departure from the in- 25 vention.

By the simple construction shown, heating systems already established may be readily provided with the improved elbow, and these elbows, in either form illustrated 30 and described, may be made of any desired dimensions or sizes to suit the capacity of the radiator.

Changes may be made in the form and proportions of my improvement, without departure from the invention which is not limited to the exact construction shown and described. So too, the form of the trap in the elbow may be variously modified, if desired, and still be within the purview of the invention in either form shown.

Having thus described my invention, what I claim is—

1. A trap having an inlet, an outlet, a diaphragm between the inlet and the outlet, and a second inlet between said diaphragm and said outlet, said second inlet being adapted to receive a pipe and the diaphragm being provided with an opening adapted to be closed.

2. A trap having an inlet, an outlet, a diaphragm between the inlet and the outlet, and a second inlet between said diaphragm and said outlet said second inlet being adapted to receive a pipe, the diaphragm having an opening adapted to be closed, and said trap having a depressed portion toward which said diaphragm is extended.

In testimony whereof I affix my signature in presence of two witnesses.

JOSEPH J. STOCKDON.
